UNITED STATES PATENT OFFICE.

HARRY T. COOK, OF NEW YORK, N. Y.

DESIGN FOR A BUTTON.

SPECIFICATION forming part of Design No. 30,713, dated May 9, 1899.

Application filed March 20, 1898. Serial No. 709,863. Term of patent 3½ years.

To all whom it may concern:

Be it known that I, HARRY T. COOK, a citizen of the United States, residing at New York, in the county of New York and State of New York, have invented and produced a new and original Design for Buttons, of which the following is a specification, reference being had to the accompanying drawings, forming part thereof, in which—

- Figure 1 is a plan or face view of a button, showing my new design; and Fig. 2, a transverse section on the line 2 2 of Fig. 1.

As shown in the drawings, the leading or material feature of my design consists of a plurality of two concentric circular beads A and B, formed on the face of the button, the outer circular bead A being at the perimeter of the button and the inner circular bead B being arranged at a predetermined distance 5 therewithin, so as to form an annular space C.

Within the annular space C may be placed any desired description, and within the inner circular bead B is a circular field or space D, within which are arranged two flagstaffs in 5 a crossed position, each provided with a folded flag, one of said flags being the American and the other the Spanish flag, and centrally of said circular space or field at E is

the representation of an eagle provided with outstretched wings, the tips of which pass 30 across the inner circular bead B and across the annular space C.

The flagstaffs and flags and the representation of the eagle are raised above the surface of the central field or space D, and within 35 the upper portion of said central field or space are a plurality of stars F, arranged in the segment of a circle, and the button is also provided centrally of its reverse side with a shank G, having a head H.

It is apparent that this design may be applicable to lockets, badges, and other similar articles.

Having fully described my invention, I claim as new and desire to secure by Letters 45 Patent—

The design for a button herein shown and described.

In testimony that I claim the foregoing as my invention I have signed my name, in 50 presence of the subscribing witnesses, this 18th day of March, 1899.

HARRY T. COOK.
